UNITED STATES PATENT OFFICE.

JOSEPH BIZAS, OF CINCINNATI, OHIO.

PROJECTILE.

1,099,784.

Specification of Letters Patent. Patented June 9, 1914.

Application filed February 25, 1914. Serial No. 820,978.

To all whom it may concern:

Be it known that I, JOSEPH BIZAS, a citizen of the United States, residing at Cincinnati, in the county of Hamilton and State of Ohio, have invented new and useful Improvements in Projectiles, of which the following is a specification.

This invention relates to projectiles and in particular to projectiles for use in destroying aerial crafts, such as aeroplanes, and airships of the balloon type, and for demolishing wireless aerials on land and on war vessels.

The primary object of the invention is to provide an aerial projectile of this character which is in the form of an elongated body having a plurality of arms normally concealed therein, but which are adapted to be projected radially from the body as the projectile is shot from the muzzle of the gun; so these arms may serve to rake through the framework of an aeroplane, the antennae of a wireless aerial, or some such target in a much more effective manner than could be accomplished by the usual form of cannon ball or other projectiles of this type.

A further object is the provision of a projectile of the class set forth which is adapted to contain an explosive, and wherein a longitudinally movable plunger is mounted for use in locking the raking arms in their inoperative positions, but which is adapted to be actuated by the initial discharge of the projectile, to release the arms before the projectile leaves the muzzle of the gun. The plunger is adapted to cause ignition of the explosive, when the movement of the projectile is retarded by impact with the target. Springs are provided for automatically throwing the raking arms into their operative positions when they are released from engagement with the bore of the piece, it being understood that the latter must be of the type wherein the bore has rectilinear grooves and lands.

A still further object of the invention is to construct the projectile in such a manner that there will be no danger of premature discharge of the explosive contents thereof and so that the raking arms may cut through a considerable area of wires or light framework, before the plunger operates to effect the explosion.

The invention consists in the features of construction, combination, and arrangement

of parts, hereinafter fully described and claimed, reference being had to the accompanying drawings, in which—

Figure 1 is a side elevation of the projectile, showing the radially movable arms of the device inoperative; Fig. 2 is a rear elevation of the same; Fig. 3 is a front elevation; Fig. 4 is a similar view showing the arms in their operative positions; Fig. 5 is a side elevation of the same; Fig. 6 is a longitudinal sectional view on line 6—6 of Fig. 1; Fig. 7 is a similar view on line 7—7 of Fig. 5; Fig. 8 is a transverse sectional view on line 8—8 of Fig. 6; Fig. 9 is a similar view on line 9—9 of Fig. 6; and Fig. 10 is a detail perspective view of the plunger.

Referring to the drawings by numerals, 1 designates the substantially cylindrical body of the projectile which is composed of a plurality of longitudinally extending sections 2, each of which is sector-shaped in transverse section. The narrow inner edges of the body sections are cut away longitudinally throughout a portion of their length to form a longitudinal medial bore for a purpose which will be described presently. Transversely extending bolt members 3 connect the rear ends of the sections 2, each bolt member being extended through two diametrically opposite sections, and the sections of the body are bound together at this end also by the cap 4 which is threaded onto this end of the body as at 5. This base cap has a plurality of compression bands 5^a projecting outward from grooves 5^b in its outer periphery, and is provided medially thereon with a non-circular projection 6 which is adapted to be engaged by a wrench or other turning tool for the purpose of applying the cap to the body, or in detaching the same therefrom. A pointed cap 7 is threaded onto the front end of the body as at 8 and has a squared portion 9 for the application of a turning tool thereto. The body sections are constructed preferably of cast iron, whereas the base and point caps are constructed of steel.

Adjacent sections 2 of the body are provided in their meeting faces with longitudinal recesses which register with each other to form a slot 10 communicating with the body bore for the reception of a radially movable raking arm or blade 11, whose rear end is pivotally connected to the body by means of the pivot pin 12. These blades 11

are constructed preferably of soft steel and have their inner edges sharpened as at 13 so that they will offer a minimum amount of resistance when they are extended from the body during the flight of the projectile, but the blades are adapted, when in inoperative position, to be disposed within the respective body slots with their outer edges flush with the outer periphery of the body.

10. The pivoted ends of the raking arms are provided rearwardly of the pivots with eyes 14 which are connected by means of short flexible members 15 with the rear end 16 of a helical extensile spring 17 which extends longitudinally through the rearmost portion of the body bore. A cable 18 is connected with the forward end 19 of the said spring and extends forwardly through the body bore to the tensioning device 20 mounted within the point cap, to the winding drum 20 of which it is connected. The operating shaft 21, upon which the drum 20 is fixedly mounted, is journaled in bearings 22, which latter are constructed so as to prevent longitudinal thrust of the shaft, and extends radially within the cap. One end of the operating shaft has a non-circular end 23 which is disposed inwardly of the lateral cap opening 24 and is adapted for engagement by a turning key such as that indicated by the numeral 25. This key may be inserted through the cap opening when it is desired to wind the drum, but must be removed therefrom before the projectile can be used. A ratchet 26 is provided upon the shaft 21 and a pawl 27 is mounted within the cap for engagement with the ratchet to prevent retrograde movement of the cable after it has been wound 40 upon the drum to place the spring 17 under the desired tension. A spring 28 is adapted to maintain the pawl normally in its operative position in engagement with the ratchet teeth.
45. An elongated rectangular plunger 29 is mounted for longitudinal sliding movement within the body bore, its longitudinal faces being frictionally engaged with the longitudinal faces of the recesses of the body section, whereby the plunger is held against rotation and is guided throughout its sliding movement. The plunger has a medial opening 30 slidably receiving the cable 18. The plunger is provided upon each corner 50 thereof adjacent to its rear end with an eye 31 for the reception of a longitudinally extending, resilient tongue 32 which is disposed within the corresponding body slot and has its rear end connected with the body by means of a pin 33. Each tongue 55 32 is placed under lateral tension when brought into its operative position for engagement within the corresponding eye of the plunger whereby it will frictionally engage the eye. An offset portion 34 is formed

upon each tongue adjacent to its free end providing limiting shoulders 35 and 36 for engagement with the eye 31 to prevent excessive longitudinal movement of the plunger under ordinary conditions, such as the handling of the projectile prior to its being placed in active use. These sustaining tongues are therefore adapted to yield, when the plunger is moved axially with sufficient force, for purposes which will be described 75 fully hereinafter.

A substantially L-shaped locking member 37 is detachably connected with each corner of the plunger adjacent to its front end for movement within the adjacent body slot 80 with its longitudinally extending portion 38 adapted for engagement within an eye 39 projecting inwardly from the free end of the corresponding raking arm, when the plunger is in its forwardly disposed locking position with its eyes 31 in engagement with the shoulders 36 of the sustaining tongues 32, so as to secure the arm in its inoperative position within the body slot against the tension of the spring 17. It should be apparent that, when the plunger 29 is moved rearwardly within the body of the projectile with sufficient force, the arms 11 will be released, whereupon they will be thrown into their operative, radially extending positions 85 by action of the spring 17. Each arm is adapted, when in operative position, to bear against the shoulder 40 provided at the rear end of the body slot in which the arm is mounted. In order to prevent too forcible impact with this limiting shoulder, a helical extensile spring 41 has one end connected with a transverse pin 42 provided within the forward portion of each body slot 10 and has its opposite end connected by means 90 of a flexible member 43 with an eye 44 provided medially upon the corresponding arm 11. The flexible member 43 is adapted to be drawn taut as the arm assumes its operative position, whereby the spring 41 serves 95 to mitigate the force of impact with the limiting shoulder. The said spring and flexible member are adapted to lie within the corresponding body slot when the arm is in its inoperative position, and when the arm is in 100 this position, it is adapted to engage the pin 42, which latter serves to prevent the free end of the arm from projecting too far into the interior of the body.

In the front and rear ends of the projectile body, chambers 45 and 46 respectively are provided for the reception of explosive material. Fuses 47 lead from the explosion chambers 45 axially to the percussion caps 48 arranged within the forward ends of the respective body slots 10 in the paths of movement of the engaging portions 38 of the members 37 carried by the plunger 29. These projecting portions 38 of the members 37 are adapted to detonate the explosives 105 110 115 120 125 130

within the chambers 45 upon the impact with the percussion caps, as caused by the excessive forward movement of the plunger 29 within the body of the projectile when 5 the velocity of the projectile is retarded to a sufficient extent by its penetration of the target. The shoulders 36 of the sustaining tongues 32 serve, by their engagement with the eyes 31 of the plunger, to hold the plunger 10 against excessive forward movement within the body of the projectile into its detonating position, during the initial portion of the penetration of a fragile target, such as an aeroplane or the antennae of a 15 wireless aerial, the final movement of the plunger into detonating position being accomplished upon further penetration. The percussion caps 48 are also connected with the rearmost explosion chamber 46 by means 20 of fuses 49, each of which extends through a longitudinal channel 50 in the inner face of each segment or section 2 of the body. Each fuse is protected by a strip of metal 51, which is secured within the enlarged 25 outer portion of the recess 50 with its exposed face flush with the face of the said body section. Owing to the provision of a number of percussion caps, which are connected with the explosion chambers, and 30 means for detonating all of the caps at a single blow, simultaneous explosion of the gun powder, nitro-glycerin, or the like, in all of the chambers will be insured. The 35 explosion of the projectile at the proper moment should serve, in addition to the effect of the raking arms, to demolish the target, particularly in the case of an aeroplane, to such an extent as to incapacitate the same for further use.

40 What is claimed is:

1. A projectile of the class described comprising a body, a plurality of arms movably mounted within said body and being adapted to project outwardly therefrom, yieldable means tending normally to maintain the said arms in extended operative position, releasable means by which the arms may be secured in inoperative position, the last-named means being adapted to be rendered 45 inoperative upon discharge of the projectile, and yieldable means for sustaining the arms securing means against operation.

2. A projectile of the class described comprising an elongated body having a plurality 50 of longitudinal slots in its outer periphery, a radially movable arm mounted within each slot and having its rear end pivoted therein, each arm being adapted to be swung outwardly into a laterally projecting position bearing against the rear end wall of the receiving slot, yieldable means tending normally to maintain the said arms in operative position, the said body being provided with a longitudinal bore in communication with the slots, a longitudinally 55 movable plunger mounted within the said bore, a laterally projecting locking member provided upon said plunger for longitudinal movement within each slot and having a forward extension, an eye member 60 provided upon each of said arms for engagement with the forward extension of the corresponding locking member, an eye member provided upon the said plunger, and a resilient, longitudinally extending member provided 65 within the body and being engaged within the eye member of the plunger.

mounted within the said bore, a laterally projecting locking member provided upon said plunger for longitudinal movement within each slot and having a forward extension, and an eye member provided upon each of said arms for engagement with the forward extension of the corresponding locking member. 70

3. A projectile of the class described comprising an elongated body having a plurality of longitudinal slots in its outer periphery, a radially movable arm mounted within each slot and having its rear end pivoted therein, each arm being adapted to be swung outwardly into a laterally projecting position bearing against the rear end wall of the receiving slot, yieldable means tending normally to maintain the said arms in operative position, the said body being provided with a longitudinal bore in communication with the slots, a longitudinally movable plunger mounted within the said bore, a laterally projecting locking member provided upon said plunger for longitudinal movement within each slot and having a forward extension, an eye member provided upon each of said arms for engagement with the forward extension of the corresponding locking member, and yieldable means provided within said body and tending normally to resist movement of the plunger sufficient to release the said arms. 85 90 95

4. A projectile of the class described comprising an elongated body having a plurality of longitudinal slots in its outer periphery, a radially movable arm mounted within each slot and having its rear end pivoted therein, each arm being adapted to be swung outwardly into a laterally projecting position bearing against the rear end wall of the receiving slot, yieldable means tending normally to maintain the said arms in operative position, the said body being provided with a longitudinal bore in communication with the slots, a longitudinally movable plunger mounted within the said bore, a laterally projecting locking member provided upon said plunger for longitudinal movement within each slot and having a forward extension, an eye member 100 provided upon each of said arms for engagement with the forward extension of the corresponding locking member, and a resilient, longitudinally extending member provided within the body and being engaged within the eye member of the plunger. 105 110 115 120

5. A projectile of the class described comprising an elongated body having a plurality of longitudinal slots in its outer periphery, a radially movable arm mounted within each slot and having its rear end pivoted therein, each arm being adapted to be swung outwardly into a laterally projecting position bearing against the rear end 125 130

wall of the receiving slot, yieldable means tending normally to maintain the said arms in operative position, the said body being provided with a longitudinal bore in communication with the slots, a longitudinally movable plunger mounted within the said bore, a laterally projecting locking member provided upon said plunger for longitudinal movement within each slot and having a forward extension, an eye member provided upon each of said arms for engagement with the forward extension of the corresponding locking member, an eye member provided upon the said plunger, and a resilient, longitudinally extending member provided within the body and being engaged within the eye member of the plunger and having an offset portion providing rounded limiting shoulders for engagement with the said eye member to resist movement of the plunger in both directions.

6. A projectile of the class described comprising an elongated body having a plurality of longitudinal slots in its outer periphery, a radially movable arm mounted within each slot and having its rear end pivoted therein, each arm being adapted to be swung outwardly into a laterally projecting position bearing against the rear end wall of the receiving slot, yieldable means tending normally to maintain the said arms in operative position, the said body being provided with a longitudinal bore in communication with the slots, a longitudinally movable plunger mounted within the said bore, a laterally projecting locking member provided upon said plunger for longitudinal movement within each slot and having a forward extension, an eye member provided upon each of said arms for engagement with the forward extension of the corresponding locking member, an eye member provided upon the said plunger, a resilient, longitudinally extending member provided within the body and being engaged within the eye member of the plunger and having an offset portion providing rounded limiting shoulders for engagement with the said eye member to resist movement of the plunger in both directions, the said body being provided with a chamber for the reception of explosive material, a percussion cap disposed in the path of the forward projection of one of said locking members, and a fuse connecting the said cap with the chamber.

7. A projectile of the class described comprising an elongated body having a plurality of longitudinal slots in its outer periphery, a radially movable arm mounted within each slot and having its rear end pivoted therein, each arm being adapted to be swung outwardly into a laterally projecting position bearing against the rear end wall of the receiving slot, yieldable means tending normally to maintain the said arms in operative

position, releasable means for securing the said arms in inoperative position, the last-named means being adapted to be rendered inoperative upon forward movement of the projectile, and resilient means for resisting the movement of each arm into its operative position.

8. A projectile of the class described comprising an elongated body having a plurality of longitudinal slots in its outer periphery, a radially movable arm mounted within each slot and having its rear end pivoted therein, each arm being adapted to be swung outwardly into a laterally projecting position bearing against the rear end wall of the receiving slot, yieldable means tending normally to maintain the said arms in operative position, and releasable means for securing the said arms in inoperative position, the last-named means being adapted to be rendered inoperative upon forward movement of the projectile, the said yieldable means for securing the said arms in inoperative position being comprised of a helical extensible spring extending longitudinally within the body, means for connecting the rear end of said spring with the pivoted end of each movable arm at a point spaced from its pivot.

9. A projectile of the class described comprising an elongated body having a plurality of longitudinal slots in its outer periphery, a radially movable arm mounted within each slot and having its rear end pivoted therein, each arm being adapted to be swung outwardly into a laterally projecting position bearing against the rear end wall of the receiving slot, yieldable means tending normally to maintain the said arms in operative position, releasable means for securing the said arms in inoperative position, the last-named means being adapted to be rendered inoperative upon forward movement of the projectile, the said yieldable means for securing the said arms in inoperative position being comprised of a helical extensible spring extending longitudinally within the body, means for connecting the rear end of said spring with the pivoted end of each movable arm at a point spaced from its pivot, and means by which the tension of the said spring may be adjusted.

10. A projectile of the class described comprising an elongated body having a plurality of longitudinal slots in its outer periphery, a radially movable arm mounted within each slot and having its rear end pivoted thereto, each arm being adapted to be swung outwardly into a laterally projecting position bearing against the rear end wall of the receiving slot, yieldable means tending normally to maintain the said arms in operative position, releasable means for securing the said arm in inoperative position, the last-named means being adapted to be rendered

inoperative upon forward movement of the projectile, the said yieldable means for securing the said arms in operative position being comprised of a helical extensible spring extending longitudinally within the body, means for connecting the rear end of said spring with the pivoted end of each movable arm at a point spaced from its pivot, a cap provided upon the front end of said body, an operating shaft journaled in said cap, a winding drum mounted fixedly upon the shaft, a flexible member having one end

connected operatively with the drum and its other end connected with the forward end of the said spring, means by which the said shaft may be rotated in one direction and means for preventing retrograde movement of the shaft in the other direction.

In testimony whereof I affix my signature in presence of two witnesses.

JOSEPH BIZAS.
